[57] CLAIM

The ornamental design for a telephone, as shown and described.

DESCRIPTION

FIG. 1 is a top plan view of a telephone, showing my new design;

FIG. 2 is a rear elevational thereof;

FIG. 3 is a side elevation thereof; and

FIG. 4 is a front perspective view thereof, with the handset removed from the base.

The characteristic features of my design reside in the specific configuration of a telephone in combination with a Statue of Liberty figurine.
